SAFETY MATCH BOX

John A. Bye, Minneapolis, Minn.

Application October 8, 1941, Serial No. 414,073

5 Claims. (Cl. 206—1.5)

This invention relates to containers and more particularly to containers which are so constructed that they can be opened only with a knowledge of the several operations which must be carried out before the container is released from its enclosing casing. The device is particularly adapted for use as a safety match box to prevent children from gaining access to the matches therein. Many children are seriously burned as a result of fires started by the children playing with matches. It is not always safe to place the matches on a shelf out of reach of the children because they can still climb upon a chair or table and secure the match box. Not only is the element of physical injury involved but a considerable amount of property is also destroyed in this manner.

It is a general object of my invention to provide a safety match box which is secured in a casing by an arrangement of latches which require several operations to release the combination of latches and the match container.

A further object of the invention is to provide latch elements and operating means therefor wherein the operating means must be accurately moved to various predetermined positions in order to successfully open the box.

Still another object of the invention is to provide a combination of latch elements wherein certain of said elements must be placed in certain predetermined positions simultaneously with the placement of others of said elements in order to release the latch container.

These and other objects and advantages of the invention will more fully appear from the following description made in connection with the accompanying drawing, wherein like reference characters refer to the same parts throughout the views, and, in which:

Fig. 1 is a perspective view of the device;

Fig. 2 is a transverse section through the upper portion thereof;

Fig. 3 is a section taken approximately on the line 3—3 of Fig. 2;

Fig. 4 is a section taken approximately on the line 4—4 of Fig. 2;

Fig. 5 is a section taken approximately on the line 5—5 of Fig. 2; and

Fig. 6 is a fragmentary detail of one of the latch members.

The device includes a backboard 6 having an aperture 7 therein so that the backboard can be placed over a nail or other supporting member. Secured to the backboard is a casing A made up of a pair of sides 8 and 9, a top 10, and a bot-

tom 11. The front of the casing is open. A match container designated generally at B includes a front 12, a back 13, sides 14 and 15 and a bottom 16. It should be noted that the sides 14 and 15 extend downwardly below the bottom 16 and are supported on pivots 17. The lower forward portions of the sides 14 and 15 are cut away as at 18 to permit the container to tilt forwardly on its pivots as indicated in Fig. 4 in dotted lines.

It should be noted in Figs. 2 and 4 that the match container B is spaced forwardly of the rear wall of the casing C. Approximately in the central portion of the casing back member 6 is a staple 19 and on the back of the match container a hook or latch 20 is pivotally mounted so that when the container is pushed into the casing said latch member 20 will engage the staple 19 as shown in Figs. 2 and 4. An arm 21 extends upwardly from the latch 20 as shown in Fig. 4, said arm and latch being movable together around the pivot 22. The bracket 23 which supports the latch 20 is preferably of channel shape and the bottom of the channel prevents the latch from falling too far down to engage the staple 19.

A shaft 24 extends horizontally across the rear portion of the casing A, the left-hand end of said shaft, as viewed in Fig. 2, being journalled in the casing side wall 8 and the right-hand end of said shaft extending exteriorly of the casing and having a crank 25 thereon. The shaft 24 carries a finger 26 which, as shown in Fig. 4, will engage the upstanding arm 21 and push it to the right as the shaft is rotated to release the latch member 20 from the staple 19.

As illustrated in Figs. 2 and 3 the shaft 24 carries a cogwheel 27. A dog 28 is pivotally mounted on the casing side wall 8 and said dog normally engages the teeth on the cogwheel 27 holding the shaft 24 against rotation. The dog 28 is held in engagement with the cogwheel by means of a lever 29 which extends through a horizontal plate 30 secured in the casing. Below the plate 30 a spring 31 is located on the lever 29 to yieldably urge said lever downwardly and keep the dog 28 in engagement with the cogwheel 27. In Figs. 2 and 4 there is shown a knob 34 and there is also shown a bentover end 29a on the rod 29 which extends through a slot 8a in the casing side wall 8 and to engage with the knob 34. The dog 28 has a slot 28a permitting the rod 29 to move as the knob 34 is rotated. Naturally rotation of knob 34 will cause the rod 29 and dog 28 to be raised thus bringing the dog 28 out of engagement with the cogwheel 27.

Mounted on the container back 13 is a lever 35 pivotally mounted at 36. Said lever 35, as shown in Fig. 4, has an angular extension made up of a pair of hinge members 37 and 38. The hinge portion 38 has an extension 38a, shown in Figs. 2 and 4, which prevents the hinge from working upwardly past center as viewed in Fig. 4. When the shaft 24 is rotated in a counterclockwise direction to release the latch 20, said shaft must be stopped at a pre-determined position since, if it is further rotated, the finger 26 will engage the hinge portion 38 and swing the lever 35 to the left so that said lever will engage the upstanding arm 21 and re-engage the latch 20 with the staple 19. The hinge 37, 38 is provided so that should the shaft 24 be rotated in the opposite direction it will merely push the hinge portion 38 to the right and cause no harm to the apparatus.

A pair of partitions 39 and 40 extend from the front to the rear of the casing A and lie closely adjacent the sides of the container B. Said partitions have arcuate slots 41 formed therein as shown in Figs. 3 and 4, said slots having pins 42 extending therethrough from the receptacle sides 13 and 14. Pivotally mounted on the partition 39 is a latch member 43 which, when the container B is pushed into the casing A, will hook over the left-hand pin 42 to further secure the container B in said casing A. A rod 44 is pivotally connected to the latch 43 and extends downwardly through the horizontal plate 30 and through the casing bottom 11. A spring 45 on the rod 44 normally urges the latch 43 downwardly so that it will remain engaged on the left-hand pin 42.

At the right-hand side of the casing a latch member 46 is pivotally mounted on the partition 40 and adapted to engage the right-hand pin 42. A latch operating rod 47 is pivotally connected to the latch 46 and extends downwardly through the casing bottom 11 and said operating rod 47 carries a spring 48 normally urging the rod 47 upwardly to keep the latch 46 in yielding engagement with the right-hand pin 42. It should be noted that to release the latch 43 it is necessary to push upwardly on the rod 44 while to release the latch 46 it is necessary to pull downwardly on the rod 47. I have also provided a pair of dummy rods 49 and 50 which extend into the casing. The rod 49 carries a spring 51 which yieldably urges the rod 49 upwardly and the rod 50 has a spring 52 thereon normally urging said rod 50 downwardly. The rod 50, as best seen in Fig. 5, is provided with a guide 50a to keep it in proper position.

The operation of the device is as follows:

The knob 34 at the left-hand side of the casing A is turned to lift the rod 29 by reason of its interconnection with the bent-over end 29a of said rod 29 and, of course, rod 29 being connected to the dog 28, the latter will be lifted out of engagement with the cogwheel 27. The crank 25 is then rotated 180 degrees to cause the finger 26 to disengage the latch 20 from the staple 19. As shown in Fig. 4, this rotation of the crank 25 and shaft 24 brings the finger 26 between the upstanding arm 21 and the hinge members 37 and 38. Further rotation of the crank 25 and shaft 24 will cause the finger 26 to engage the hinge portion 38 and cause the lever 35 to swing to the left and reset the latch 20.

With the latch 20 disengaged from the staple 19 the latch operating rod 44 is pressed upwardly and at the same time the latch operating rod 47 is pulled downwardly whereupon the match container B will swing outwardly from the casing A

and rest at an angle approximately that shown in Fig. 4.

When the match container B is pushed back into casing C the device is again in position for operation, the catches having all been reset automatically. The knob 34 is reset due to the tension of the spring 31, and, of course, the latch 20 will naturally snap into the staple 19. Obviously latches 43 and 46 and dog 28 will engage their respective cooperating parts.

Although the device appears to be rather complicated to a person first learning its operation it is in fact a very simple matter for one familiar with the construction to quickly actuate the catches and open the container.

While I have described my invention as being useful as a safety match box it will be understood that the device might find a use as a puzzle box since one unacquainted with its operation would find it extremely difficult to get open.

It will, of course, be understood that various changes may be made in the form, details, arrangement and proportions of the various parts without departing from the scope of my invention.

What is claimed is:

1. In a safety match box and the like, a casing, a match container movable into and out of said casing, a first latch member within said casing releasably securing said container in said casing, means for locking said latch against movement, said locking means being movable to a pre-determined position to release said latch for movement to unlock the latter, a pair of additional latch members within said casing securing said container in said casing, said pair of latch members having operators extending out of the casing, one of said pair of latch operators being movable in one direction to release its latch and the other of said pair of latch operators being movable in the opposite direction to release its latch.

2. The structure in claim 1 and a pair of dummy latch operators positioned adjacent said first mentioned pair of latch operators and movably extending into said casing but being disconnected from any of said latches and said container.

3. In a safety match box and the like, a casing, a match container movable into and out of said casing, a latch member within said casing releasably securing said container in said casing, a latch operator extending exteriorly of said casing, means for locking said latch operator against movement, actuating means for said latch operator locking means extending exteriorly of said casing, said latch operator locking means being movable to a pre-determined position to release said latch operator, and being further movable to again lock said latch operator when moved past said pre-determined position, and said latch operator being movable to a pre-determined position to release said latch, means engageable by said latch operator for again securing said latch when said operator is moved past its pre-determined releasing position.

4. In a safety match box and the like, a casing, a match container movable into and out of said casing, a latch member within said casing releasably securing said container in said casing, a rotary latch operator extending exteriorly of said casing, said latch operator including an element adapted to engage said latch and adapted to contact said latch to release the same when said operator is in a pre-determined position, and a

latch reset element in the path of movement of said latch operator and movable to re-engage said latch when said operator is rotated beyond its pre-determined position.

5. In a safety match box and the like, a casing, a latch container movable into and out of said casing, a latch member within said casing releasably securing said container in said casing, a latch operator shaft in said casing and having a por-

tion extending exteriorly thereof to permit its rotation from the outside of said casing, a cogwheel on said shaft within said casing, a dog in said casing movable into and out of engagement with said cog-wheel, dog actuating means extending exteriorly of said casing, and a latch releasing element on said shaft movable into and out of engagement with said latch.
